PLATE ASSEMBLING AND RETAINING JACK

Ferruccio Martini, New York, N. Y.

Application April 2, 1943, Serial No. 481,631

3 Claims. (Cl. 113—99)

This invention relates to a novel and improved jack which is expressly, though not necessarily, adapted to facilitate the assembling of plates such as for example those used in the construction of ship hulls, and the like, the construction being such as to promote maintenance of the adjacent edges of coacting plates in overlapping relation to aid in welding the plates together.

Needless to say, I am aware that many different types of devices, tools and clamps, and certain types of jacks have been provided with a view toward rendering convenient the assembling of flat and equivalent plates for expeditious welding purposes. With such information in mind, I have evolved and produced a specific construction which is industrially appropriate, expertly balanced and of great utility in aptly serving the intended purposes. It follows, therefore, that my primary aim is to generally improve upon known marketed and patented jacks and equivalent devices by providing one which is mechanically superior, compact and convenient, simple and reliable, and such as to save time and labor in achieving new and useful results.

Furthermore, I have comprehended the problem and, through the wise choice and selection of appropriately usable elements, have provided a novel arrangement wherein coordination between the parts chosen is assured and capable of being relied upon.

Other features and advantages will become more readily apparent from the following description and the accompanying illustrative drawings.

In the drawings, wherein like numerals are employed to designate like parts throughout the views:

Figure 1 is a top plan view of the jack and particular construction thereof, as devised in accordance with the principles of this invention, showing the same in use in association with overlapping plates.

Figure 2 is an enlarged section taken vertically on the plane of the line 2—2 of Figure 1, looking in the direction of the arrows.

Figure 3 is an enlarged fragmentary view showing one of the slidable adapter fixtures for one of the jacking or feed screws.

Figure 4 is a section on the plane of the line 4—4 of Figure 3.

Figure 5 is a fragmentary view showing the inner end construction of one of the jack screws, illustrating the swiveled thrust head.

Figure 6 is a section, enlarged, on the plane of the line 6—6 of Figure 1.

Figure 7 is a fragmentary perspective view

showing one of the temporarily tack welded lugs employed in the arrangement.

The main or yoke-like unit is conveniently referred to as a portable frame 8. It comprises a horizontal, longitudinally elongated foundation bar 9, this having right angularly disposed limbs 10a at its opposite ends. The free end portions of the limbs 10 are curved to bear against one of the plates A or B, as the case may be. These members 10 are for bracing and stress distribution and strain equalizing purposes. As constructed and shown, they are especially efficient in contributing their proportionate share to the general combination of parts. The limbs 10 also serve to carry the brackets 11. Each bracket is in the form of an arm having a reduced end portion 12 terminating in a T-shaped head. The head is formed into selectively usable, appropriately curved anchoring hooks 13 and 14.

Attention now comes to the slides or fixtures 15. Generally, I have provided two of these, and they are in the form of parts 16 having clips 17 which take over the longitudinal edges of the bar 9. Each fixture is provided with an adapter 18 of tubular form, the bore of which is provided with screw threads 19 to accommodate the jack or feed screw 20. The screw 20 has a suitable head 21 on its outer end to accommodate the shiftable rod or handle 22. The opposite end of the screw is provided with a thrust head 23 swivelly mounted in place as shown in Figure 5. Thus, we have a substantially U-shaped frame with braces 10 bearing against the plates and shiftable adapter fixtures 15 carrying the thrust or feed screws, these being parallel to each other and located between the limbs 10.

In practice, lugs or ears 24 (see Fig. 7) are temporarily tack-welded, as at 25, to the desired positions on the plates A or B, as the case may be. Each lug is provided with an aperture 26 to accommodate the anchoring hooks 13 and 14. Incidentally, the structure is such as to be reversible, that is, the limbs 10 may be down against the plate A, or the entire frame structure can be turned over through one-half revolution and thus serve to position the same limbs against the plate B. However, the principle of operation is the same regardless of whether the limbs are up or down. That is to say, the hooks 13 are engaged in the lugs 24, as shown in Figure 2, to couple the brackets 11 to the limbs 10. Then, the feed screws are backed out against the plate B to bring the thrust heads 23 in position as shown. The feed screws are slightly above the brackets 55 so as to enable the coacting brackets and feed

screws in conjunction with the frame structure to press the plates A and B firmly together in overlapping relation, whereby to facilitate accomplishing the welding result.

I feel that I have perceived, through experimentation and study, a structure susceptible of advantageous results. The arrangement is complete and workable. In fact, it is believed that there is herein embodied in the structure a wise choice in the selection and coordination of appropriately usable parts and elements. 10

It is thought that persons skilled in the art to which the invention relates will be able to obtain a clear understanding of the invention after considering the description in connection with the drawings. Therefore, a more lengthy description is regarded as unnecessary. 15

Minor changes in shape, size, and rearrangement of details coming within the field of invention claimed may be resorted to in actual practice, if desired.

I claim:

1. In a structure of the class described, in combination, a pair of plates having adjacent edges overlapped, apertured lugs tack-welded on one of the plates adjacent the overlapping portions, a U-shaped frame having a central horizontal bar and longitudinally curved end limbs adapted to engage the first-named plate, brackets carried by said limbs and having hooks releasably engageable with the lugs, slides on the central bar portion of the frame, and jack screws mounted in said slides. 25

2. A plate assembling and retaining jack comprising a horizontal elongated bar having limbs rigid with and extending downwardly from opposite ends thereof, said limbs being curved downwardly and forwardly to bear against a plate at their lower ends, forwardly projecting brackets on the upper portions of said limbs having anchoring hooks at their forward ends for engagement with ears welded to said plate near its upper edge, fixtures carried by said bar near its opposite ends, and jack screws threaded forwardly through said fixtures to bear at their forward ends upon the lower edge portion of a second plate overlapped upon the upper edge portion of the first-named plate. 10

3. A plate assembling and retaining jack comprising a horizontal elongated bar having limbs rigid with and extending downwardly from opposite ends thereof, said limbs being curved downwardly and forwardly to bear against a plate at their lower ends, forwardly projecting brackets on the upper portions of said limbs having anchoring hooks at their forward ends for engagement with ears welded to said plate near its upper edge, fixtures carried by said bar near its opposite ends, and jack screws threaded forwardly through said fixtures to bear at their forward ends upon the lower edge portion of a second plate overlapped upon the upper edge portion of the first-named plate, said fixtures being slidable on and longitudinally of said bar. 20 30

FERRUCCIO MARTINI.
